UNITED STATES PATENT OFFICE

171,995

HANDBAG

Sheldon J. Aberman, Miami Beach, Fla.

Application December 3, 1953, Serial No. 27,874

Term of patent 3½ years

(Cl. D87—3)

To all whom it may concern:

Be it known that I, Sheldon J. Aberman, a citizen of the United States of America, residing in Miami Beach, county of Dade, and State of Florida, have invented a new, original, and ornamental Design for a Handbag, of which the following is a specification, reference being had to the accompanying drawing, forming part thereof, wherein,

I claim:

The ornamental design for a handbag, substantially as shown.
